UNITED STATES PATENT OFFICE.

LAURENCE A. DICKSON, OF MEMPHIS, TENNESSEE.

MUSICAL MECHANICAL TOY.

1,276,626.

Specification of Letters Patent. Patented Aug. 20, 1918.

Application filed October 18, 1917. Serial No. 197,316.

To all whom it may concern:

Be it known that I, LAURENCE A. DICKSON, a citizen of the United States, residing at Memphis, in the county of Shelby, State 5 of Tennessee, have invented certain new and useful Improvements in Musical Mechanical Toys, of which the following is a specification.

The present invention relates to musical 10 mechanical toys.

An object of this invention is to provide a rolling toy which may be controlled by hand to produce a mechanical sound when operated; to provide the toy with means 15 for interrupting the mechanical sound and at will during the operation of the toy; to provide a toy embodying a novel construction for producing wind pressure; and to provide a toy with novel means for producing wind by the utilization of wind 20 pipes or the like.

Another object of the present invention is to provide a relatively strong and simply constructed toy capable of withstand- 25 ing hard usage; which requires but little pressure in its operation, and a toy which may be economically manufactured.

The above and various other objects and advantages will be in part described and 30 in part understood from the following detailed description of the present preferred embodiment, the same being illustrated in the accompanying drawings wherein:

Figure 1 is a side elevation of a musical 35 toy constructed according to the present invention.

Fig. 2 is an end elevation of the same.

Fig. 3 is a fragmentary longitudinal ver- 40 tical section through the upper portion of the pneumatic, the wind chest and one of the pipes, the controlling valve being also shown.

Referring to the drawings, 10 designates a cross-piece which constitutes the body of 45 the frame and to the opposite ends of which is secured a pair of lugs 11 constituting bearings for an axle 12 provided near opposite ends and at the inner sides of the lugs 11 with crank portions 13. Wheels 50 14 are fixed upon the opposite ends of the axle 12 at the outer sides of the lugs 11, are adapted to support the toy and are adapted by their traction with the ground to rotate the axle 12.

55 The cross-piece 10 is provided with a suitable tongue or handle 15 by means of

which the toy may be propelled by hand or otherwise. The cross-piece 10 also carries a leaf spring 16 which extends upwardly and is suitably curved, substantially S-shaped, to form a resilient support. 60 Fixed to the upper end of the support is a lower leaf 17 of a pneumatic, the leaf 17 overhanging the axle 12 and the frame of the toy. A hinged leaf 18 is connected to the fixed leaf 17 at the tongue end of the toy and is connected near its free end by links 19 to the crank portions 13 at opposite sides of the pneumatic. This pneumatic or bellows has secured across its upper 70 side, and preferably at its hinged end a wind chest 20 which communicates with the pneumatic through a pipe or neck 21 which is secured directly over the outlet opening 22 formed in the upper leaf 18 75 of the bellows. The wind chest 20 carries a plurality of pipes or whistles 23 of the desired length and constructed to produce sound by vibration of air passing into the pipes 23 from the wind chest 20. The upper end of the neck 21 is open, and a plug valve 24 is adapted to close the same at times, the valve 24 being carried upon an arm 25 hinged at 26 upon the neck 21 and being normally held in position to open the 80 valve 24 by spring 27 secured at opposite ends respectively to lever 25 and the outer end of the wind chest. The lever 25 is preferably returned upon itself and has secured to its free end a cord 28 which extends in 85 the direction of the handle or pull 15 and may be manually drawn sufficiently taut to overcome the spring 27 and close the valve 24. When the valve 24 is closed, and the wheels 14 are turned, the air compressed 90 by the bellows or pneumatic is directed from the neck 21 into the wind chest 20 and subsequently into the tubes 23. The bellows has an air intake opening 29 in the lower leaf 17 and is inclosed by flexible 100 wall 30 which is secured about the marginal edges of the leaves 17 and 18.

It is believed that the operation of the device is apparent for when the handle 15 is either drawn or pushed the wheels 14 105 travel over the ground and operate the hinged leaf 18 of the bellows through the links or connecting rods 19. Air is taken into the bellows through opening 29 when the bellows is expanded and the flap valve 110 of the opening closes upon the collapse of the bellows whereupon the air is emitted

through the outlet opening 22. A child drawing the toy need only pull the string 28 to close the valve 24 when it is desired to sound the whistles or pipes.

5 It is, of course, understood that various changes and modifications may be made in the details of construction and design of the above specifically described parts of this invention without departing from the spirit 10 thereof, such changes and modifications being restricted only by the scope of the following claims.

I claim:—

1. In a musical toy, the combination of a 15 wheeled frame, a plurality of sound tubes mounted on the frame, an air compressing means on the frame and having connection with the wheels to actuate the compressing means by movement of the frame, and having connection with the tubes for simultaneously sounding the same.

2. In a musical toy the combination of a 25 frame, wheels supporting the frame and bellows on the frame, a connection between the wheels and the bellows for operating the latter, an open neck connected to the bellows, a sound tube connected to the neck, and a valve adapted to close the neck to deflect wind pressure from the bellows to the 30 tube.

3. In a musical toy the combination of a 35 frame, a bellows mounted on the frame, wheels supporting the frame and connected to the bellows for operating the same, an open neck communicating with the bellows, a valve carried by the neck, means for maintaining the valve normally open, operating

means connected to the valve for closing the same at times, a wind chest communicating with the neck to receive air therefrom when the valve is closed, and a plurality of sound tubes communicating with the wind chest.

4. In a musical toy the combination of a 45 frame, a bellows on the frame, wheels supporting the frame and connected to the bellows for operating the same, a neck leading from the bellows, a wind chest communicating with the neck, a plurality of sound tubes connected to the wind chest, and means for controlling the passage of air 50 from the neck to the wind chest.

5. In a musical toy the combination of a 55 frame, a crank shaft journaled in the frame, wheels connected to the crank shaft for supporting the frame and turning the shaft, a bellows having one leaf mounted on the frame, connecting rods between the other leaf of the bellows and the cranks of said shaft, a plurality of sound tubes communicating with and supported upon the bellows, and means for controlling the passage 60 of air from the bellows to the tubes.

6. In a musical toy the combination of a 65 frame, a crank shaft journaled in the frame, traction wheels fixed upon the crank shaft for turning the same and supporting the frame, a bellows mounted on the frame, a connection between the crank shaft and the bellows for opening and closing the 70 latter, a plurality of sound tubes, and a manually controlled connection between the bellows and the sound tubes.

LAURENCE A. DICKSON.
